UNITED STATES PATENT OFFICE.

R. E. HITCHCOCK, OF WATERBURY, CONNECTICUT.

PICTURE-BUTTON.

Specification of Letters Patent No. 33,038, dated August 13, 1861.

To all whom it may concern:

Be it known that I, R. E. HITCHCOCK, of Waterbury, in the county of New Haven and State of Connecticut, have invented a new and Improved Picture-Button; and I do hereby declare that the following is a full, clear, and exact description of the same, reference being had to the accompanying drawing, forming a part of this specification, in

10 which—

Figure 1, represents a vertical central section of a button or medal with two pictures. Fig. 2, is an inverted plan of one of its parts detached. Fig. 3, is a vertical central section of a button with one picture.

15 Similar letters in the three figures indicate corresponding parts.

To enable those skilled in the art to make and use my invention I will proceed to describe it with reference to the drawing.

20 My buttons or medals are made of two parts. The medals are made of two rims A, A, such as represented in Fig. 2, which consists of a cup shaped piece a, of sheet iron, to which a piece of cloth or velvet b, of the desired color is fastened by an eye c, of brass having its edges bent over on both sides as clearly shown in Figs. 1, and 2, or in any other desirable manner. One of the 25 two rims is a little smaller than the other as clearly shown in Fig. 1, so that the cloth or velvet coverings b, can be turned over the edges of the cup shaped piece a, and the rim A', can now be inserted into the rim A, and 30 if both are pressed together, the cloth or velvet is firmly retained between the inner 35

cup a' and the outer cup a. The pictures d, are placed between the two rims A, A', as clearly shown in Fig. 1, and if it is desired a loop e, may be fastened between the two 40 rims so that the medal can be suspended from or hung up to any desired place.

If I want to produce a button, the rim A', is dispensed with, and instead of the same the ordinary back B, of a button is inserted 45 into the rim A, the cloth or velvet covering of said rim being pressed in and held in its place by said back. In this case only one picture d, is used, and the button can now be attached to a garment or to any other place 50 with the same convenience as an ordinary button and by the use of cloth or velvet for the covering I am enabled to adapt its color to the article with which it is to be used, and by having the pictures on the buttons I 55 can give to the same the desired variety.

I do not claim broadly the invention of picture buttons nor medals, but,

Having thus fully described my invention, what I claim as new and desire to secure by 60 Letters Patent as an improved article of manufacture, is,

A picture medal or button, constructed with cups a', a' or back B' in lieu of one of the cups, eyes c, pictures d and cloth or velvet covering b and otherwise made as herein shown and described.

R. E. HITCHCOCK.
